ABSTRACT: A distributor for internal combustion. The distributor has a rotary cam provided with a number of lobes, and these lobes are respectively provided with marks which precisely indicate the crests of the lobes. A breaker plate surrounds the cam and carries a swingable contact arm one end of which is successively engaged by the cam lobes. This end of the contact arm and the breaker plate are respectively provided with marks which when respectively aligned with a pair of the marks of a pair of cam lobes indicate that the points are set at their widest gap, so that it then becomes possible to adjust the gap between the points.

IMPROVED ADJUSTMENT MEANS FOR DISTRIBUTOR CONTACTS AND BEARINGS

BACKGROUND OF THE INVENTION

The present invention relates to distributors used in internal combustion engines for distributing the spark in a given sequence among the cylinders of the engine.

As is well known it is necessary from time to time to adjust such distributors so that the breaker points thereof will have a given gap therebetween. In order to adjust the gap between the breaker points of such distributors, so as to achieve an accurate setting of these points, the points are first situated at a location providing the maximum or widest gap therebetween. Once this latter position is reached, it is possible to proceed in a very accurate manner to provide the desired setting of the gap between the points.

One of the difficulties encountered with conventional distributors resides in the fact that it is extremely difficult to determine when the points are set at their widest gap. If the distributor remains connected with the engine, it is necessary to determine this maximum gap setting by eye, and the inherent inaccuracies in such procedures result in undesirably poor settings of the breaker points. It has therefore become customary in the practice to remove the distributor from the engine and to utilize relatively expensive testing and tuning equipment in order to achieve an accurate setting for the breaker points. However, unless the vehicle which has the distributor is located at a shop which is sufficiently large and well equipped to be provided with such testing and tuning equipment, equipment of this latter type simply is not available and the result is poor settings of the breaker points because of the unavoidable inherent inaccuracies, as set forth above.

In addition, in order to provide a smooth accurate operation for the distributor it is essential that the camshaft which carries the distributor cam rotate in good bearings so that an accurate rotary movement of the cam about its axis can be assured. After operation of a distributor over a given period of time the bearings of the camshaft become worn with the result that the accuracy of the operation of the distributor suffers. When the play of the shaft in the bearings becomes sufficiently great it is necessary to recondition the distributor in order to again achieve the best possible operation. However, at the present time it is difficult to determine when the reconditioning is necessary. In this case also it is only by eye or by a sense of feel that a mechanic will judge the necessity of reconditioning the distributor because the bearing play is too great, and with these latter procedures there are unavoidable inaccuracies resulting either in reconditioning of distributors which do not require reconditioning or in lack of reconditioning where such reconditioning is indeed required.

SUMMARY OF THE INVENTION

It is accordingly a primary object of the present invention to provide a distributor structure which will avoid all the above drawbacks.

In particular, it is an object of the invention to provide a distributor with a structure which will very readily indicate when the breaker points are at their widest gap, without requiring the distributor to be removed from the engine.

In addition, it is an object of the invention to provide a structure which can accomplish this result while increasing the cost of the distributor to a minimal extent.

Furthermore, it is an object of the invention to provide for distributors various color codes for indicating markings so that the settings can be made for distributors to be used with engines having different numbers of cylinders.

Furthermore, it is an object of the invention to provide a construction of the above general type which will indicate precisely the extent of wear of the bearings, so that an accurate indication of the necessity for reconditioning can be achieved.

With the structure of the invention a rotary cam of the distributor is provided with visible marks which respectively coincide with the crests of the cam lobes. A breaker plate surrounds the cam and the plate carries a swingable contact arm which has an end which is successively engaged by cam lobes during rotary movement of the cam, as is well known. This end of the contact arm and the breaker plate itself are respectively provided with a pair of marks which when respectively aligned with a pair of marks of a pair of the cam lobes accurately position the distributor in a condition where the points thereof are at their maximum distance from each other. In this way it becomes possible to achieve very accurately, without removing the distributor from the engine, an initial position where the widest gap between the points prevails, so that thereafter it is a simple matter to achieve the required accurate setting of the gap between the points.

BRIEF DESCRIPTION OF DRAWINGS

20 The invention is illustrated by way of example in the accompanying drawing which forms part of this application and in which a distributor is shown in a top plan view provided with the structure of the invention, the cover being removed from the distributor housing so as to clearly illustrate the structure therein.

25 Referring to the drawing, the entire distributor 10 illustrated therein is conventional except for the indicator markings and graduations as referred to below. Thus with the present invention it is only required to alter a conventional distributor by providing it with suitable indicator marks, so that the cost involved in providing a distributor in accordance with the present invention is hardly more than the cost of a conventional distributor.

30 The distributor 10 has a conventional housing 12 which at its bottom wall 14 supports, in a known way, a shaft 16 for rotary movement within a suitable unillustrated bearing. This shaft 16 carries a cam 18 which rotates with the shaft, and this cam has a series of cam lobes 20, as is well known. The cam 18 carries a plurality of marks 22 of the invention, and these marks are in the form of relatively short lines extending radially from the axis of the shaft 16 and respectively coinciding with the crests 24 of the cam lobes.

35 The housing 12 carries in its interior, in a well-known manner, a breaker plate 26 formed with a central opening 28 in which the cam 18 is accommodated. Thus, the plate 26 surrounds the cam 18. This plate 26 carries, as is also conventional, a spring-pressed swingable contact arm 30. This arm 30 has an end 32 also of conventional construction which is successively engaged by the lobes 20 as the cam 18 rotates with the shaft 16. In this way during the oscillatory swinging of the arm 30 the points 34a and 34b will be moved into and out of engagement with each other in a well-known manner so as to make and break the electrical circuit which provides the energy for the actuation of the spark plugs to achieve sparks in the cylinders in a given sequence.

40 In accordance with the invention the end 32 of the contact arm 30 is provided with a mark 36 and the breaker plate 26 is itself provided with a mark 38 angularly displaced through 90° with respect to the mark 36 about the axis of the camshaft. With this construction when one of the marks 22 on the cam 18 is aligned with the mark 36 on another of the marks 22 is aligned with mark 38, the points 34a and 34b are at their maximum from each other, thus achieving a maximum gap between these points. Once this latter condition is accurately achieved it is a simple matter to provide an accurate setting of the gap between the points in a well-known manner. Thus it becomes possible with this construction to provide the widest gap between the breaker points in an exceedingly simple and highly accurate manner without removing the distributor from the engine.

45 The marks 22 on the cam can be provided in accordance with a given color code. Thus one set of marks of a given color 50 can be displaced by 90° with respect to each other about the

camshaft axis for 4-cylinder engine. A different color can be used for marks displaced by 60° with respect to each other about the camshaft axis for 6-cylinder engines. In the case of 8-cylinder engines, a still further distinctive color can be used for a set of marks which will be displaced from each other by 45° about the camshaft axis. Of course, in all of these cases the engines are 4-cycle engines. However, similar angles can be used for 2-cycle engines since the marks scribed on the cam can be placed where the cam will open the breaker points to their widest gap.

It is also possible with the structure as shown in the drawing to determine the extent of bearing wear. Thus, with the parts in the position shown in the drawing, the operator need only push the shaft 16 toward the arm 30, or more precisely the end 32 thereof and the mark 36 on this end 32. This will result in displacement of that mark 22 which is aligned the mark 38 laterally with respect to the latter. It can be judged from the extent of lateral displacement of such a mark with respect to the mark 38 whether it is necessary to recondition the bearing. In other words the extent of displacement under these conditions will give an indication of the extent of wear of the bearings.

However, in this case also, in order that there be no guess-work in the determination of whether or not reconditioning is required, the breaker plate 26 is provided with a plurality of additional graduations 40 one of which is formed by the mark 38 which is preferably located centrally between the end graduations of the series of graduations 40. Thus, it is possible to determine the number of graduations along which the mark 22 which is aligned with the mark 38 is displaced when pushing on the camshaft 16. In this way the operator will know, for example, that if the extent of displacement is only through a distance of one or two graduations the distributor does not require any reconditioning whereas if the displacement is through three or more graduations then reconditioning is under all circumstances essential.

It is thus apparent that with the simple structure of the invention it becomes possible on the one hand to very precisely determine the maximum width of the gap between the points so that an accurate adjustment of the points can be made, and on the other hand the extent of bearing wear can also be determined so that a decision can be made with respect to whether or not reconditioning of the distributor is required.

I claim:

1. In a distributor for an internal combustion engine, a rotary cam having a plurality of lobes, a breaker plate surrounding said cam, and a swingable contact arm carried by said plate and having an end successively engaged by the lobes of said cam during rotary movement of the latter, said cam carrying at least two marks visible and aligned with two lobes of said cam, and said end of said arm and said breaker plate respectively carrying visible marks which when aligned

respectively with said marks of said cam automatically situate breaker points of the distributor at their widest gap, so that thereafter the width between said points may be adjusted.

2. The combination of claim 1 and wherein said cam has more than two lobes, and all of the lobes of said cam being respectively provided with marks so that any selected pair of said marks may be respectively aligned with said marks on said arm and plate to determine the widest gap between the breaker points.

10 3. The combination of claim 2 and wherein the marks on said cam are provided with a color code according to which one set of marks of one color are angularly displaced with each other by 90° for 4-cylinder engines, another set of marks are of a different color and separated from each other by 60° for 6-cylinder engines, and a third set of marks have a distinguishing color and are separated from each other by 45° for 8-cylinder engines, with all of said engines being 4-cycle engines.

15 4. The combination of claim 1 and wherein said marks on said end of said arm and said breaker plate are angularly displaced from each other about the axis of said cam by 90° .

5 5. The combination of claim 4 and wherein said breaker plate carries a series of graduations one of which coincides with said mark on said breaker plate, so that a camshaft which carries said cam, upon being pushed toward said arm, will displace the mark aligned with said breaker plate mark through a distance indicative of the degree of wear in bearings, so that an indication is provided of a requirement for reconditioning of the distributor.

20 6. The combination of claim 5 and wherein said mark on said breaker plate is situated midway between the first and last of the series of graduations.

7. In a distributor for an internal combustion engine, a rotary cam having a plurality of lobes, a breaker plate surrounding said rotary cam, at least one mark carried by said cam at one of said lobes thereof, and at least one additional mark carried by said plate to be aligned with said mark on said cam, whereby when said marks are aligned a shaft which carries said cam can be pushed in a direction perpendicular to a radial line extending through the axis of said cam and the aligned marks, thus displacing the cam mark with respect to the plate mark to provide an indication of the degree of wear of the camshaft bearings, so as to indicate whether or not reconditioning of the distributor is required.

45 8. The combination of claim 7 and wherein said breaker plate has graduations one of which coincides with said mark on said breaker plate for indicating the degree of wear of the bearings.

9. The combination of claim 8 and wherein said graduations are situated on both sides of the mark of said breaker plate with the latter centrally located between the ends of the series of graduations.
